METHOD AND APPARATUS FOR COOLING
BUFFS AND POLISHING WHEELS

Joseph R. Davies, Chicago, Ill.

Application September 8, 1950, Serial No. 183,724

5 Claims. (Cl. 51—267)

1

This invention relates to a method and apparatus for cooling grinding and polishing surfaces, and particularly to cooling the cores or central portions of buffs, polishing wheels and belts.

The quality and speed of grinding, buffing and polishing is very dependent upon the heat of operation of the buff or wheel. The heat is generated at the periphery and a substantial portion is dissipated in the air. However, there is a substantial and steady flow of heat from the periphery inwardly toward the hub and as this heat in the hub cannot be dissipated quickly, it steadily increases, and if the grinding or buffing operation is not at least temporarily terminated, the buff may burn, but even before burning, the cloth may lose its tensile strength due to the heat, and deteriorate. In the case of grinding or polishing wheels wherein the cloth layers at the surface are cemented together with glue which holds the grinding powder, the cloth expands under the heat and chunks of cloth, grinding compound and fabric may crack off the periphery, necessitating complete refinishing of the wheel. Indeed, where polishing wheels are being pushed to their limit, in getting out rush work, the heat has caused the polishing wheel to explode right on the job.

This is an old problem and has been partially solved by designing buffs and components of polishing wheels with radial passageways for air from the hub toward the periphery. These passageways in the case of buffs pass through the periphery and provide a certain amount of cooling. In the case of the polishing wheels, the passageways are usually parallel with the axis around which the wheel rotates and there is little or no passage of air through the periphery which is quite hard due to the presence of glue and grinding powder. Despite these air passageways, buff and polishing wheel temperatures build up so that the operation must be stopped if the maximum life of the buff is to be attained.

It occurred to the applicant that the method of dissipating heat in buffs and polishing wheels in the past was inadequate because they depended upon the circulation of air which has a very limited capacity to absorb heat, as does any gas. In order to absorb an appreciable amount of heat collected in the body of a buff or polishing wheel an enormous amount of air or any gas must be flowed through said body. If water could be used, a comparatively large amount of heat could be taken up with small quantities, particularly where the water passes from a liquid into a vapor state. Bearing in mind that it requires 536 times

2

as many calories to vaporize a quantity of water at 212° as is required to raise its temperature by one degree centigrade, it is self-evident that a great deal of heat can be removed whenever vaporization takes place.

Applicant proceeded to investigate the burning temperatures of materials used in buffs and polishing wheels. The burning temperature of cotton was not lower than 220° Fahrenheit, that is, eight degrees above the boiling point of water. The vast majority of buffs are made of cotton material. There are piece buffs made of textile remnants, and these remnants may include small amounts of silk, linen and wool, but these fibers are comparatively rare. There are also some buffs made of sisal and jute. Here again, the volume is small compared to cotton. In the case of sisal and jute, however, the burning or flash point is higher than cotton. Applicant thereupon realized that he could keep buffs from burning by keeping the core wet.

However, this does not solve very much in the case of either buffs or grinding wheels because if a whirling grinding wheel will centrifugally expel air, a fortiori it will expel water and this water will adversely affect the grinding compound on either a buff or a polishing wheel.

The general object of this invention is to cool buffs, polishing wheels and polishing belts by evaporating small particles of a liquid such as water on the surfaces of the buffs and carrying away the vapor in a gas such as air.

The invention is specially adapted for use with the so-called "ventilated buffing wheels" which are in common use today. In these wheels the buffing sections are spaced from each other by a fraction of an inch so as to provide passageways from the hub to the periphery. There is a limited amount of circulation of air due to centrifugal action, and a specific object of this invention is to introduce small water particles to this air which will deposit themselves on inner surfaces of the buffing section and will then be evaporated when the buff temperature rises to a selected point.

A second specific object of this invention is to introduce air under pressure near the hub of these buffing sections so as to increase substantially the circulation of vaporizable water particles through the buff.

The invention may also be adapted to polishing wheels, grinding wheels and abrasive belts. As the peripheral surfaces of these abrasive media are almost impervious to the passage of air, it is a specific object of this invention to provide

means for introducing fine particles of water into air passageways near the polishing wheel hubs and through which there is a flow of air.

Another object of this invention is to control the amount of cooling liquid particles that are introduced into the abrasive media so that the minimum temperature necessary to flow the metal of the work at the point of contact can be maintained while nevertheless preventing excessive temperatures back toward the center of the wheel. By eliminating excessive temperatures, not only is the cloth of which the abrasive media is formed preserved from deterioration, but particularly in the tightly packed polishing and grinding wheels, bad effects due to expansion of the material are avoided.

These and such other objects as may herein-after appear are attained in the description of the method and the embodiment of the invention shown in the accompanying drawings wherein:

Fig. 1 is a view in vertical side section of a ventilated buffing wheel on a shaft with applicant's apparatus mounted on one side thereof;

Fig. 2 is a vertical side section of a polishing wheel having a modified form of applicant's apparatus for introducing water particles mounted on either side thereof;

Fig. 3 is a view taken on the line 3—3 of Fig. 1; and

Fig. 4 is a schematic illustration of a simplified apparatus to practice applicant's method.

Continuing to refer to the drawings, in Fig. 1, the numeral 10 identifies a shaft upon which is mounted four buffs 12, 14, 16 and 18, which are held in spaced relationship by shoulders 20, and constitutes a ventilated buffing wheel. The particular type of buff is not important. The buffs illustrated are annuluses, each mounted on a core made of wood or steel. A plurality of solid buffs, that is, buffs in which the core portion is formed integrally with the buff itself, as for example, the buff sections 22 shown in Fig. 2, may be used. The important thing is that the buff sections be spaced from each other so as to provide air passageways 24 radially directed.

Transversely through these buff sections or cores of buff sections are passageways 26 which intercept the radial passageways 24 so that there may be a flow of air from the former, through the latter and to the working periphery of the buff. The buff sections are held in assembled relationship by a solid plate 30 and a plate 32 having holes 34 alignable with passageways 26.

The structure now to be described is more schematic than realistic or commercial. It illustrates experimental apparatus. Mounted on the shaft 10, adjacent the plate 32 is a collar 36 upon which is mounted a bearing assembly 38 which in turn carries a wheel 40. This wheel 40 consists of a hub 42, spokes 44 and a tubular rim 52 from which projects inwardly nozzles 54.

A bell 56 is mounted outside the collar 36 on the shaft 10 and is held thereon by nut 37. The bell's outer edge 57 is positioned close to the circumferential edge of the plate 32. A conduit 58 taps the tubular rim 52 and passes through an opening 60 in the bell 56 to a tank of water under pressure 64. Mounted externally of the bell 56 and concentrically of the shaft 10 is a circular tube 66 having holes 68 through its inside wall in alignment with openings 70 in the bell. These openings 70 are in alignment with the passageways 26 through the buff sections. The circular tube 66 is connected by a tube 72 through a valve 74 to a source of compressed air 76.

The operation of the apparatus is as follows. As the buffing operation is commenced and the buff rotates, comparatively little air is thrown radially because there are no vanes in the passageways 24 to cause circulation. The wheel 40 and the bell 56 assembly remains motionless. A valve 78 in the water line is opened and a spray is produced in the annular area 80. This spray is not vaporized water but fine particles of water which are momentarily suspended in the air. Concurrently, the valve 74 is opened and compressed air is introduced through the plurality of openings 70 which in turn blows the mist at 80 into the passageways 26. Since the passageways 24 are the only means of escape for the air, the air is forced outwardly.

Many of the water particles deposit themselves on the surfaces of the buff between the point 82 and the periphery. As the temperature of the buff rises, the deposited water particles will vaporize and in so doing, will remove heat from the buff. The air flowing in the passageways 24 will carry the vapor and heat out of the buff section.

It is seen that applicant's method consists in the step of adding minute water particles to exposed surfaces centrally of a buff and of then providing a carrier, that is, the air, to remove the vapor evolved from these water particles after their temperature has exceeded a certain point. Applicant regulates the flow of water into the buff core so as not to get the cores too wet. The quantity of water introduced will vary depending upon the kind of buffing work that is being done. If the work is such that high temperatures are caused in the buff, additional water will be carried into the buff.

Applicant has experimented with other apparatus to accomplish this same result. Thus, in Fig. 1, the tank 64 is shown as containing water only and the mist effect is obtained by the nozzles 54. Applicant has been experimenting with a device for producing a mixture of air and water in a tank such as 64 and forcing this mixture of water and air into the areas 80. Under these circumstances, he does not rely upon nozzles to attain the desired diffusion of water particles.

He has also considered the construction illustrated in Fig. 4. Here a buff 90 is schematically shown with transverse passageways 92 and radial passageways 94. A compressed air tank 96 is connected through a hose 98 to an atomizing head 100. To the bottom of this head is fastened a jar filled with water 102. The nozzle 104 is aligned with the passageways 92 which due to the revolution of the buff will successively pass the nozzle 104. This arrangement is considerably simpler than the structure shown in Fig. 1 but is not quite as effective because since the air is blown into only one of the passageways 92 at a time, and since these passageways are connected to each other interiorly of the buff core, the air currents are set up in conflicting directions instead of entirely radially. This is to be contrasted with the bell arrangement shown in Fig. 1 where once the air enters the buff, it enters through all of the passageways 26 at the same pressure and consequently the water particles are carried to the various parts of the buff fairly uniformly.

Thus far applicant has been describing the cooling of a buff, by which he means a disk structure whose peripheral surface is formed of comparatively loose threads uncompacted by gelatine, glue and grinding compound. Grinding compound may be applied to the surface of these 75 buffs, but the surface is nevertheless flexible and

loose. The invention is also beneficial for use on a polishing wheel. A polishing wheel might be formed of the very same buff sections that are shown in Fig. 1, but generally is formed of solid buff sections as illustrated in Fig. 2. These sections are not spaced from each other and hence no substantial quantity of air can move radially from the hub to the periphery. Also, the polishing wheel periphery is hard as it carries a mixture of grinding compound and glue. Common practice is to punch holes through the assembled wheel parallel to the axis, as for example, 106 in Fig. 2. In this figure, the water atomizing assembly is identical with that shown in Fig. 1. However, the compressed air connection is omitted. This compressed air connection could be mounted on the assembly in Fig. 2 as in Fig. 1, and the water particles driven into the passageways 106 as heretofore described. However, in this assembly, applicant has mounted on the right-hand side of the shaft a collar 110 which carries a bell 112 held on a shaft by a nut 114. An opening 116 in the bell wall is connected to a suction pump 120 by a conduit 118. The suction pump creates a partial vacuum inside the bell and while there is substantial leakage at the points 120 and 122, the pressure at the point 124 is substantially below atmospheric pressure and there is a flow of air through the passageways 106. This flow of air picks up the small water particles and more slowly carries them into the passageways 106 and 108 where they are deposited on the walls. As the temperature of the polishing wheel rises near its hub, these water particles vaporize and take up heat and are withdrawn through the bell on out through the suction pump.

Applicant's method of cooling buffing and polishing wheels can also be applied to grinding wheels and belts. Essentially, the idea is to deposit particles of water on some surface of the buffing media which acquires heat from the work surface but which itself is not part of that surface, and then when these water particles vaporize and take heat out of the buff material, to carry off the vapor and to re-deposit more water particles. In certain kinds of operations, a belt is passed over a wheel between the wheel and the article to be buffed and thence over another wheel which is the driving wheel. The belt passes through air and is cooled. Applicant's idea would be to spray the back of the belt with water particles which in turn will vaporize and cool the belt.

In order to simplify the language of the claims, the words "buffs" and "buffing" include not only what are technically known as "buffs" or "buffing" in the trade, but also polishing and grinding wheels and belts made of the materials referred to in this specification.

Having thus described applicant's invention, what he claims is:

1. A buffing assembly comprising a shaft, flexible buffing units rotatably mounted on said shaft, a side opening through the walls of the buffs parallel and adjacent to the shaft, means spacing the buffs from each other near the hub so as to form air passageways connecting the first-mentioned opening to the inner side surfaces of the buffs, the flexibility of the buffing units being such that during operation the peripheral surface is substantially continuous so that the air passageways from the hub to the periphery are interrupted by the flexible material of the buffing unit, means for forcing an air stream under pres-

sure into said opening and against the inner side walls of the buffs, and means for introducing particles of water into said air stream at a point near said opening.

- 5 2. A buffing assembly comprising a shaft, flexible buffing units rotatably mounted on said shaft, a side opening through the walls of the buffs parallel and adjacent to the shaft, means spacing the buffs from each other near the hub so as to form air passageways connecting the first-mentioned opening to the inner side surfaces of the buffs, the flexibility of the buffing units being such that during operation the peripheral surface is substantially continuous so that the air 10 passageways from the hub to the periphery are interrupted by the flexible material of the buffing unit, means for forcing an air stream under pressure into said opening and against the inner side walls of the buffs, and a liquid atomizing means 15 mounted adjacent the entrance to said side opening in the walls of the buff and in the path of the air stream.

- 20 3. The method of cooling circular buffing elements composed of layers of inflammable, flexible 25 disks of fabric which comprises the steps of impinging vaporizable liquid particles on the side walls of said disks in amounts sufficiently small so that the peripheral working surface does not become wet, and of carrying off the vapor resulting from the particles contacting the hot surface in a flow of radially directed air.

- 30 4. In the method of cooling circular buffing elements composed of layers of inflammable, flexible 35 disks of fabric wherein air is introduced adjacent the hub for circulation radially along the side surfaces of said disks, the step of adding liquid particles to the air prior to its passage radially along the surfaces of the disks in such 40 small quantities that the particles, upon engagement with the side surfaces of the disks, will vaporize and not wet the peripheral working surface of the buff.

- 45 5. The method of cooling rotating, circular buffing elements composed of layers of inflammable, flexible disks of fabric which comprises the steps of introducing air between the surface of said disks adjacent the hub and of suspending finely divided particles of water in said air immediately prior to its introduction to the buffing 50 element and in such small quantities that the water will vaporize on contact with the disks and not wet the peripheral work surface.
